FOLLOW-UP MOTOR CONTROL SYSTEM

Louis Hegy, Burbank, Calif., assignor to Bendix Aviation Corporation, South Bend, Ind., a corporation of Delaware

Application October 9, 1945, Serial No. 621,347

2 Claims. (Cl. 318—33)

1

This invention relates to electrical systems for selectively controlling the movements of a motor-driven mechanism into any one of a plurality of predetermined positions, and is particularly useful with power-driven multi-position actuators adapted to be stopped in any one of a relatively large number of positions.

An object of the invention is to provide a control system that is positive and reliable in operation over long periods of use, and that is relatively simple and inexpensive to manufacture.

Another object is to reduce the number of conductors required in an electric control system for a multi-position actuator.

Other more specific objects and features will appear from the detailed description to follow of a particular embodiment of the invention as illustrated in the drawing.

The invention has application to motor driven devices adapted to be driven either in one or both directions and stopped in any one of a plurality of positions under the joint control of a master selector switch and of a motor-driven switch, both of which switches have a number of positions corresponding to the number of positions in which the device is adapted to be stopped.

In such systems, where multi-position switches having a relatively large number of positions are employed, it is highly desirable from the standpoint of cost, compactness, and weight, to employ what are commonly referred to as wafer switches. Wafer switches employ light contacts riveted or otherwise attached to a light annular plate of insulating material and adapted to be wiped by a light moving contact which is usually also mounted on a thin plate of insulating material, which is adapted to be rotated by a shaft. However, wafer switches have been considered unsuitable for control circuits in which they are required to break appreciable currents. In accordance with the present invention, wafer switches can be employed in multi-position power-driven actuators, because the arrangement is such that the contacts of the wafer switches are not broken while they are carrying current. This result is achieved by the use of special auxiliary switches of snap action type which function to interrupt the current flow in the circuits extending through the wafer switches before the contacts of the latter break, in combination with an extra wafer switch contact, which reduces the number of leads between the control and controlled station.

Other more specific features of the invention

2

will become apparent from the description to follow with reference to the drawing in which

Fig. 1 is a schematic diagram of a control system in accordance with the invention;

Fig. 2 is an end view of a wafer switch assembly employed in the system; and

Fig. 3 is a cross-section taken in the plane III—III of Fig. 2.

Referring first to Fig. 1, there is shown a reversible electric motor 10 having a shaft 11 bearing a drive pinion 12, which meshes with a driven gear 13, which in turn drives a controlled shaft 14 through a Geneva mechanism. This Geneva mechanism includes a slotted disk 15 on the shaft 14 and a locking sector 16 and drive pin 17 mounted on the side of the gear 13. When disk 15 is in any one of six different positions of rest, it is locked in such position by engagement of the sector 16 in one of six arcuate recesses 15a in the periphery of the disk 15. However, when the disk 15 is to be shifted into a different position, such movement is accomplished by energizing the motor 10 to rotate the gear 13 through one or more revolutions. Rotation of the gear 13 carries the segment 16 out of locking relation with the recess 15a in which it was engaged, and simultaneously carries the pin 17 into one of six radial slots 15b in the disk 15. Continued movement of the pin 17 rotates the disk 15 through one-sixth of a revolution, after which the pin 17 leaves the slot 15b, and the sector 16 simultaneously engages a new recess 15a to lock the controlled shaft 14 in a new position. It will be observed that one revolution of the gear 13 carries the disk 15 through one-sixth of a revolution, and it will be apparent that the disk can be moved in either direction through any desired distance in increments of 60° by driving the gear 13 through a desired number of complete revolutions.

The system of Fig. 1 includes a circuit controlled jointly by a master selection switch 18 and by a follow switch 19 driven by the controlled shaft 14. Movement of the master selection switch 18 into a different position completes a circuit through the follow switch 19 to start the motor running in one direction or the other, to drive the controlled shaft 14 into the desired new position, and the follow switch 19 functions to interrupt the energizing circuit of the motor 10 when the controlled shaft 14 has reached its desired position.

The master switch 18 comprises a shaft 18a on which are mounted: a handle 18b; a cam disk 18c actuating a snap action switch 18d; and the ro-

tatable element 18e of a wafer switch having a movable contact 18f which is permanently connected to a fixed contact 18g, and is movable into six different positions, in which it contacts with six different fixed contacts 18h which are connected respectively to six conductors 1, 2, 3, 4, 5 and 6 extending to the follow switch 19.

The shaft 18a is connected through a friction drag switch 18j with a continuing shaft 18k on which is mounted an arm 18p adapted to operate switch contacts 18m and 18n, according to the direction of rotation of the shaft 18a.

The follow switch 19 is a double wafer switch comprising two rotatable contacts 19a and 19b mounted on an insulating support 19c, which is connected to the controlled shaft 14 for rotation therewith. The rotatable contact 19a makes contact at all times with a stationary contact 19d and has an extension 19e which is adapted to connect with different ones of six stationary contacts 19f in six different positions of the controlled shaft 14. The movable contact 19b, instead of having a finger thereon, has a recess or gap 19g, and in any position of rest of the controlled shaft 14, the contact 19b contacts with five of six contacts 19h, but is open with respect to the remaining contact 19h because of the gap 19g.

The different stationary contacts 19h and 19f are connected respectively to the lines 1, 2, 3, 4, 5 and 6, and it will be observed that the recess 19g in the rotatable contact 19b and the extension 19e of the rotatable contact 19a are juxtaposed to each other so that as each of the lines is disconnected from the contact 19b, it is connected to the line 19a.

The movable contact 19b is permanently connected to a contact 19j, which is connected by a conductor 20 to the contacts 21 and 22 of the reversing switch. This line 20 is also connected to one terminal of a cam-actuated switch 23, the other terminal of this switch being connected to the contact 19d. The switch 23 is closed by a cam 24 on a shaft 25 extending from the gear 13, which functions to close the switch 23 while the pin 17 is in driving relation with any one of the slots 15b of the driven member 15.

The motor 10, as shown, is of the series type having an armature 10a, brushes 10b and 10c, and two field windings 10d and 10e respectively, these field windings being oppositely poled so that the motor runs in one direction when one field winding is energized and in the other direction when the other field winding is energized. One of the brushes 10c is connected by a conductor 27 to one terminal of a current source 28. The other brush 10b is connected to a common terminal of the two field windings 10d and 10e, the other terminals of these field windings being connected by conductors 29 and 30 to the reversing switch contacts 18m and 18n respectively. The other terminal of the current source 28 is connected by a conductor 30 to one terminal of the switch 18d, the other terminal of this switch being connected to the contact 18g.

It will be observed that in any position of the master selection switch 18, one terminal of the current source 28 is connected through the conductor 30 and the switch 18d, and thence through the contact 18g and the contact 18f to one of the lines 1, 2, 3, 4, 5 or 6, and, when the system is at rest, the contact 19h of the switch 19 associated with this line will be juxtaposed to the recess 19g, while the contact 19f that is connected to this line will be closed on the extension 19e and

will be connected through contact 18d to one terminal of the switch 23, which is normally open. Hence, the motor is not energized.

However, if the handle 18b is rotated into a new position, current will flow from the source 28 over the conductor 30 through the switch 18d and over the switch contacts 18g and 18f to another of the lines 1, 2, 3, 4, 5 or 6, which line will be connected through its associated contact 19f and the movable contact 19b and the stationary contact 19j to the conductor 20 through the contacts 21 and 22. If the handle 18b was moved clockwise, then the arm 18p was rocked clockwise by the friction clutch 18j to open contact 18m away from contact 21 and close contact 18n on contact 22, thereby completing a circuit from conductor 20 over contacts 22 and 18n and through the field winding 10d and armature 10a of the motor 10, and thence through conductor 27 back to the other side of the current source 28. The field winding 10d is so poled that it causes the motor 10 to rotate in such direction as to drive the controlled shaft 14 in the same direction that the handle 18b was turned (clockwise, in this instance).

The motor 10 drives the gear 13, which in turn drives the controlled shaft 14 through the Geneva mechanism until the recess 19g in the movable contact 19b is carried into registration with the contact 19h that is connected to the energized line. However, the motor 10 is not stopped immediately upon movement of the recess 19g into the disconnect position with respect to the live contact 19h, because the corresponding contact 19f is simultaneously connected to the extension 19e and thence through the contact 19d to one terminal of the switch 23. As has been previously pointed out, the switch 23 is closed by the cam 24 whenever the controlled shaft 14 is being rotated. Therefore, prior to the breaking of the connection from the energized line by the recess 19g, the conductor 20 is connected by the switch 23, the contact 19d, the moving contact 19a and the extension thereof 19e, to the energized line so that the circuit to the motor 10 is not interrupted by the opening of the connection between the movable contact 19b and that one of the stationary contacts 19h that is connected to the energized line. However, the motor is stopped when it has reached the desired position, by opening of the switch 23 by the cam 24.

If the control handle 18b is turned clockwise into still another position, the operation described is repeated to move the controlled member 14 into the new position.

If the control handle 18b is turned counter-clockwise, the system functions as described except that the motor 10 then runs in the opposite direction because the friction clutch 18j will then open the contacts 18n and 22 and close the contacts 21 and 18m to energize the field winding 10e of motor 10. The switch 19 and the switch 23 function in the same manner regardless of the direction of rotation of the motor 10.

If reversible operation is not desired, the reversing switch, including the elements 18j to 18n inclusive, can be eliminated together with one of the motor windings 10d or 10e and the remaining winding connected permanently to the conductor 20. This eliminates the necessity of extending conductors 20, 28 and 29 to the master switch 18.

It is to be particularly noted that the use of the double wafer switch 19 having the extra contacts 19a, 19d and 19f eliminates the necessity of running a separate lead from the upper ter-

rninal of the switch 23 back to the current source 28. This feature is highly desirable in control systems for use on airplanes in which the current source 28 may be located a substantial distance from the motor 10 and its associated switches, because the weight of the extra contacts provided on the wafer switch 19 may be substantially less than the weight of an additional conductor extending from the switch 23 to the current source 28.

It is also to be noted that the use of the auxiliary switch 18d in series with the wafer switch contact 18g has the important advantage of eliminating any possibility of the wafer switch contacts breaking while current is flowing, which would produce destructive arcing in a wafer switch. As is previously indicated, both the switch 18d and the switch 23 can be of the snap action type, although for simplicity they are indicated only schematically in the drawing.

Although for the purpose of explaining the invention a specific embodiment thereof has been described in detail, the invention is to be limited only to the extent set forth in the appended claims.

I claim:

1. In a control system of the type described: a controlled member movable into a plurality of predetermined different positions, and electrically controlled power means for driving it; a current source; a follow switch driven by said controlled member, and a master switch, said switches each having a plurality of different positions corresponding to said predetermined positions of said controlled member; a plurality of lines extending from said master switch to said follow switch; said follow switch comprising a first selector contact connecting with all of said lines except one and having a second selector contact connecting with only that line that is discontinued from said first selector contact in any of said positions of said controlled member; means including said master switch for completing a current path from said first selector contact of said follow switch to any one of said lines at the master switch, said path including in series relation said current source and said power means; and auxiliary switching means actuated by said controlled member into closed position as said controlled

member approaches each of said positions and into open position as said controlled member reaches each of said positions, said auxiliary switching means being connected in series between said first and second selector contacts.

2. In a system of the type described: a controlled member movable into a plurality of predetermined different positions and electrically controlled power means for driving it; a current source; a master switch for completing a circuit to said power means for driving said controlled member into a new position, and a follow switch driven by said controlled member for stopping the controlled member in the selected position, said switches each having a plurality of different positions and contacts corresponding to said predetermined positions of said controlled member; a plurality of lines extending from said master switch to said follow switch; means including said master switch and follow switch for completing a current path including said current source and said power means in series relation for driving said controlled member into a new position corresponding to a new position of said master switch, and for opening said current path in response to movement of said controlled member into said new position; in which said master switch comprises a multi-position selector switch having separate line contacts connected to said respective lines and a selector contact movable over said line contacts, and an auxiliary single circuit make and break switch connected in series with said selector contact, with means for opening said auxiliary switch prior to opening of said selector contact from each line contact and closing it following closure of said selector contact on the next line contact.
